REFRIGERATING APPARATUS

Elmer L. Horlacher, Dayton, Ohio, assignor to
 General Motors Corporation, Dayton, Ohio, a
 corporation of Delaware

Application April 29, 1943, Serial No. 484,991

5 Claims. (Cl. 62—89)

My invention relates to refrigerating apparatus and particularly to a refrigerated food storage cabinet having a refrigerating system associated therewith employing an air cooled condenser.

An object of my invention is to provide an improved air cooling arrangement for the condenser of a refrigerating system associated with a refrigerator cabinet.

Another object of my invention is to provide an improved arrangement of a condenser of a refrigerating system with respect to an air flue, provided on a cabinet housing the system, whereby the flue forming means and condenser cooperate to permit cooling of a portion of the condenser by air flowing toward the flue inlet and cooling of another portion of the condenser by air flowing through the flue.

A further and more specific object of my invention is to provide a refrigerator cabinet with a flue and to arrange the flue forming means so that a part of it divides or partitions a condenser of a refrigerating system associated with the cabinet into a portion disposed within the flue and another portion exteriorly of the flue forming means, whereby circulating cooling air is first directed through one portion of the condenser and thence directed through another portion thereof.

In carrying out the foregoing objects, other objects and advantages in the structure and in the cooperation of parts of the structure will become apparent from the illustration and the following description, wherein a preferred form of the embodiment of the present invention is shown.

In the drawing:

Fig. 1 is a front elevational view of a refrigerator cabinet having my invention embodied therein;

Fig. 2 is an enlarged vertical section of the refrigerator cabinet illustrated in Fig. 1 and is taken on the line 2—2 thereof showing the flue and condenser arrangement of the present invention; and

Fig. 3 is a fragmentary rear view of the refrigerator cabinet shown in Figs. 1 and 2.

Referring to the drawing, for illustrating my invention, I have shown in Fig. 1 thereof a refrigerating apparatus of the household type including a cabinet 10 having walls 11 forming or enclosing a food storage chamber 12, surrounded by any suitable insulating material 14 (see Fig. 2). The outer cabinet walls 11 extend beyond the insulated chamber 12 to form a machine compartment 15 below the chamber. The food cham-

ber 12 is provided with an access opening normally closed by a door 16. A door or panel 17 normally closes the front of compartment 15 and a plate or the like 18 cooperates with the outer cabinet side walls 11 to close the bottom of the machine compartment. A means such as a metal member or sheath 21 is spaced from the cabinet back wall 11 by legs 22 to form an air flue 24 extending vertically along the back of the cabinet. Screws or the like 23 (see Fig. 3) pass through a foot portion of the legs 22 and are secured to the cabinet back wall to hold the member or sheath 21 in place. The back of the machine compartment 15 is open or is provided with an opening and the lower part 25 of the flue forming means or sheath 21 overlaps the upper portion of the open back of compartment 15 to provide an air inlet for the flue 24 which inlet faces and is in communication with the interior of compartment 15. A portion 26 of the flue forming means 21 is bent inwardly toward compartment 15 to form a bottom wall for the flue and its inlet. The flue 24 is thus provided with an intake at a low level and has its outlet located adjacent the top of cabinet 10.

A refrigerating system associated with the refrigerator 10 includes an evaporator 31, for cooling the interior of food storage chamber 12, a motor-compressor unit 32, located in compartment 15, and a condenser 33 all connected by conduits in closed circuit relation. The compressor of the motor-compressor unit 32 withdraws evaporated or gaseous refrigerant from the evaporator 31, through conduit 36, compresses the refrigerant and forwards the compressed refrigerant, through conduit 37, into the upper portion of condenser 33. Refrigerant condensed in condenser 33 flows, through the liquid refrigerant conduit 38, into the evaporator 31 where it is again evaporated to remove heat from the food storage chamber 12. Any suitable or conventional thermostatic switch (not shown) may be employed for starting and stopping the motor of the motor-compressor unit 32.

The condenser 33 may be of any conventional type and is herein shown as comprising a plurality of horizontally extending tubes or conduits 41 connected at their ends to vertically disposed headers 42 (see Fig. 3). The tubes or conduits 41 have a plurality of metal fins 43 disposed vertically thereon in spaced apart relation for aiding in dissipating heat from refrigerant in the condenser. It will be noted that in the present disclosure, the condenser is secured, by suitable brackets 46, to a base plate 47 upon which the

motor-compressor unit 32 is mounted. The base plate 47 is secured to and supported upon angle iron members 48 extending across the compartment 15. This mounting of the condenser 33 locates same along the back wall of cabinet 10 in a position whereby it extends or traverses substantially the entire opening in compartment 15. The condenser 33 is so positioned and is of such height that the greater portion thereof is disposed within the flue 24 adjacent its inlet, or, in other words, the lower part 25 of the flue forming means 21, overlapping the upper portion of the open back wall of compartment 15, also overlaps the upper portion of the condenser 33. Bent-in part 26 of the flue forming means 21 abuts against the fins 43 on condenser 33 to maintain the part 25 of member 21 spaced from the condenser. The portion of condenser 33 below the flue forming means 21 is disposed in the path of air adapted to enter the machine compartment 15 in a manner and for the purpose to be presently described. Thus the overlapping of a greater part of the condenser 33 by the lower part 25 of the flue forming means 21 partitions the condenser into an upper portion disposed within the flue 24 adjacent its inlet and another portion disposed exteriorly of the flue.

Operation of the motor-compressor unit 32 of the refrigerating system causes the compressor thereof to deliver hot compressed refrigerant to the upper portion of condenser 33 and the temperature of this portion of the condenser increases above the temperature of the room in which the refrigerator is located. The heat of the upper portion of condenser 33 causes a natural draft or thermo-syphon circulation of air to be created in the flue 24. Heat is dissipated from the upper portion of condenser 33, by the circulation of air thereover, and rises in the flue 24 and is discharged near the top of the refrigerator cabinet. This movement of warm air in the flue causes cooler air from a low level in the room to be drawn into compartment 15 and flue 24. The air entering compartment 15 flows substantially in a horizontal direction over the lower portion of the condenser 33. The air upon entering compartment 15 flows upwardly and toward the inwardly facing inlet of flue 24. This air upon entering the flue 24 flows over the upper portion of condenser 33 and thence upwardly through the flue. The compressed refrigerant is partially cooled in the upper portion of condenser 33, overlapped by the part 25 of the flue forming means 21, by air passing thereover and the refrigerant is further cooled and liquefied by cooler air passing over the lower or exposed portion of the condenser. The temperature of liquid refrigerant collecting or accumulating in the lowermost portion of condenser 33 is efficiently reduced and substantially cool fully liquefied refrigerant flows, from the lower portion of one of the headers 42, by way of conduit 38, toward the evaporator 31 of the refrigerating system.

By the arrangement described and illustrated various advantages are afforded. The location of the outlet of the flue at a point adjacent the top of the refrigerator cabinet remote from the flue inlet prevents warm air flowing out of the flue from directly affecting the cooler air at a lower level in the room which flows into the machine compartment and the air flue. This location of the flue outlet, a substantial distance above the flue inlet, permits the heat of the condenser to induce the natural draft or thermo-syphon air circulation described. The air circu-

lation continues as long as any heat is dissipated from the motor-compressor unit located with the machine compartment and/or the condenser of the refrigerating system irrespective of whether or not the unit is operating. By overlapping a portion of the condenser with a part of the flue forming means or member so as to dispose the upper portion of the condenser within the flue and its lower portion exteriorly thereof air flowing into the machine compartment and through the flue is caused to flow several times over or through the condenser and the refrigerating system associated with the refrigerator cabinet is rendered more efficient in operation.

While the form of embodiment of the invention as herein disclosed constitutes a preferred form, it is to be understood that other forms might be adopted, as may come within the scope of the claims which follow.

What is claimed is as follows:

1. A refrigerating apparatus comprising in combination, a cabinet having a plurality of walls forming a food storage chamber and a machine compartment therein, a refrigerating system associated with said cabinet including an evaporator for cooling the interior of said food chamber, a refrigerant compressing unit within said compartment, a condenser and conduits connecting said evaporator, said unit and said condenser in closed circuit relation, said machine compartment having an opening in one wall thereof, means forming an air flue along a wall of said cabinet, said condenser being mounted along the opening in said compartment wall, said flue forming means having a part thereof extending over a portion of the opening in said compartment wall and overlapping a portion of said condenser to provide the flue with an air inlet facing said compartment and communicating with the interior thereof, and said part of said flue forming means partitioning said condenser into a portion disposed within said flue adjacent the inlet thereof and another portion exteriorly of said flue forming means and disposed in the path of air adapted to enter said compartment through the opening in said one wall thereof.

2. A refrigerating apparatus comprising in combination, a cabinet having a plurality of walls forming a food storage chamber and a machine compartment therein, a refrigerating system associated with said cabinet including an evaporator for cooling the interior of said food chamber, a refrigerant compressing unit within said compartment, a condenser and conduits connecting said evaporator, said unit and said condenser in closed circuit relation, said machine compartment having an opening in one wall thereof, means forming an air flue along a wall of said cabinet, said condenser being mounted along the opening in said compartment wall, said flue forming means having a part thereof extending over a portion of the opening in said compartment wall and overlapping a portion of said condenser to provide the flue with an air inlet facing said compartment and communicating with the interior thereof, said part of said flue forming means partitioning said condenser into a portion disposed within said flue adjacent the inlet thereof another portion exteriorly of said flue forming means and disposed in the path of air adapted to enter said compartment through the opening in said one wall thereof, and means abutting said condenser and cooperating with

said flue forming means for spacing said part thereof from the condenser.

3. A refrigerating apparatus comprising in combination, a cabinet having a plurality of walls forming a food storage chamber and a machine compartment therein below said food chamber, a refrigerating system associated with said cabinet including an evaporator for cooling the interior of said food chamber, a refrigerant compressing unit within said compartment, a condenser and conduits connecting said evaporator, said unit and said condenser in closed circuit relation, means forming an air flue along the back wall of said cabinet, the back wall of said machine compartment being open, said condenser being mounted along the open back wall of said compartment, said flue forming means having a part thereof extending over a portion of the open back wall of said compartment and overlapping a portion of said condenser to provide the flue with an air inlet facing said compartment and communicating with the interior thereof, and said part of said flue forming means partitioning said condenser into an upper portion disposed within said flue adjacent the inlet thereof and a lower portion exteriorly of said flue forming means and disposed in the path of air adapted to enter said compartment through that portion of said open back wall thereof below said part of said flue forming means, and means abutting said condenser and cooperating with said flue forming means for spacing said part thereof from the condenser.

4. A refrigerating apparatus comprising in combination, a cabinet having a plurality of walls forming a food storage chamber and a machine compartment therein below said food chamber, a refrigerating system associated with said cabinet including an evaporator for cooling the interior of said food chamber, a refrigerant compressing unit within said compartment, a condenser and conduits connecting said evaporator, said unit and said condenser in closed circuit relation, means forming an air flue along the back wall of said cabinet, the back wall of said machine compartment being open, said condenser

being mounted along the open back wall of said compartment, said flue forming means having a part thereof extending over a portion of the open back wall of said compartment and overlapping a portion of said condenser to provide the flue with an air inlet facing said compartment and communicating with the interior thereof, said part of said flue forming means partitioning said condenser into an upper portion disposed within said flue adjacent the inlet thereof and a lower portion exteriorly of said flue forming means and disposed in the path of air adapted to enter said compartment through that portion of said open back wall thereof below said part of said flue forming means, and means abutting said condenser and cooperating with said flue forming means for spacing said part thereof from the condenser.

5. A refrigerating apparatus comprising in combination, a cabinet having a plurality of walls forming a food storage chamber and a machine compartment, a refrigerating system associated with said cabinet including an evaporator for cooling the interior of said food chamber, a refrigerant translating unit within said compartment, a condenser, and conduit means connecting said evaporator, said unit and said condenser in closed circuit relation, said machine compartment having an opening in one wall thereof for admission of air thereto, an air flue along a wall of said cabinet, said flue having an air inlet communicating with the interior of said compartment, said flue partitioning said condenser into a portion disposed therein and another portion exteriorly of the flue and disposed in the path of air adapted to enter said compartment through the opening in said one wall thereof, and said portion of said condenser within said flue augmenting flow of air therein to provide increased circulation of air into said compartment over said another portion of said condenser.
